UNITED STATES PATENT OFFICE.

MICHAEL P. VUCASSOVICH, OF WELLESLEY HILLS, MASSACHUSETTS.

DESIGN FOR A BUTTON, PIN, OR BROOCH.

48,659.

Specification for Design.

Patented Feb. 29, 1916.

Application filed December 9, 1915. Serial No. 66,016. Term of patent 7 years.

To all whom it may concern:

Be it known that I, MICHAEL P. VUCASSOVICH, a citizen of the United States, residing at Wellesley Hills, in the county of Norfolk and State of Massachusetts, have invented a new, original, and ornamental Design for Buttons, Pins, or Brooches, of which the following is a specification, reference being had to the accompanying drawing, forming part thereof.

The figure is a plan view of a pin illustrating my new design.

I claim—

The ornamental design for a button, pin, or brooch as shown.

MICHAEL P. VUCASSOVICH.
